UNITED STATES PATENT OFFICE.

GORDON V. PLANTE, OF ATLANTA, GEORGIA, ASSIGNOR TO DIXIE PATTERN & MACHINE WORKS, OF ATLANTA, GEORGIA, A CORPORATION OF GEORGIA.

BENDING-MACHINE.

1,088,619.

Specification of Letters Patent.

Patented Feb. 24, 1914.

Application filed October 29, 1912. Serial No. 728,485.

To all whom it may concern:

Be it known that I, GORDON V. PLANTE, a citizen of the United States, residing at Atlanta, in the county of Fulton and State of Georgia, have invented new and useful Improvements in Bending-Machines, of which the following is a specification.

The present invention relates to improvements in metal bending machines and more especially to those employed in bending tubing or rods for various purposes, such, for example, as in the manufacture of iron beds and other structures, and the primary objects of the invention are to provide a generally improved machine of this type which is capable of withstanding the stresses incident to the bending of the metal, enabling it to bend tubing or rods of large sizes without straining the machine, one which is capable of bending metal, particularly tubing, without deforming it in cross-section, and which may be readily adjusted to form bends of different angles, either singly or simultaneously, and from either side of the machine.

Another object of the invention is to provide power-operated means for adjusting the distance between the bending dies whereby the distance between the bends in a length of tubing may be varied as desired.

Another object is to provide means for automatically terminating the bending operation when a bend of the desired degree has been made.

A further object of the invention is to provide improved means for maintaining the bending die members in coöperative relation during the bending operation whereby the stress to which the parts are subjected is sustained without strain of the machine and the die members may be quickly and easily opened to receive the tubing and closed to the proper degree preparatory to the bending operation.

To these and other ends, the invention consists in certain improvements, and combinations and arrangements of parts, all as will be hereinafter more fully described, the novel features being pointed out particularly in the claims at the end of the specification.

In the accompanying drawing:—Figure 1 is an elevation of a metal bending machine constructed in accordance with the present

invention; Fig. 2 is a top plan view of the machine; Fig. 3 represents a vertical section of one end of the machine taken through one pair of the bending die members and showing the power devices for operating the bending mechanism and for adjusting the distance between the bending dies; Fig. 4 represents a transverse section through the machine on the line 4—4 of Fig. 1; Fig. 5 is an end elevation of the machine as viewed from the right in Fig. 1, the driving mechanism for the machine being omitted; Fig. 6 is a detail view, partly in section, of the driving mechanism for the machine and the controlling devices therefor; Fig. 7 is a perspective view showing one of the bending dies and its coöperating die block, the upper member of the die being separated from the lower member thereof.

Similar parts are designated by the same reference characters in the several views.

The different features of the present invention are applicable generally to metal bending machines of different types, although these improvements are especially adapted to machines of the type embodying means for producing two bends simultaneously. The present invention is shown in connection with a machine of this type in the accompanying drawing and will be so described in the specification, but it will be understood that the invention is not restricted in this respect and that equivalent constructions are to be included by the claims at the end of the specification.

In the present instance, the machine embodies a bed 1 of suitable length having longitudinally extending rails 2 formed at the top thereof. A pair of slides 3 and 4 are mounted on the bed and are shiftable longitudinally on the rails 2. The slides rest on the rails and the rails coöperate with the slides to prevent lateral displacement thereof. The slides are also provided with clamping plates 5 and 6 which coöperate with overhanging portions of the rails, and bolts 7 and 8 connect these clamping plates to the respective slides. When the slides are to be shifted on the bed for the purpose of varying the distance between them, the bolts 7 and 8 are loosened, and after the slides have been adjusted as desired, these bolts are tightened, thereby securing the slides rigidly and firmly to the bed, enabling the slides to

sustain the stresses imposed thereon incident to the bending of the metal as well as preventing displacement or a change in adjustment of the slides.

5 The slides are provided with bending dies 9 and 10 and coöperating die blocks 11 and 12. The construction of the dies and die blocks on the two slides is, in the present instance, the same, and, hence, a description of 10 one will suffice for both. According to the present invention, a die of circular form is preferably employed, as a die of this form enables bends of different degrees to be made and it also enables a bend in the form of a 15 complete circle to be made. To enable the die to make bends greater than a semi-circle and to facilitate removal of the bent material from the die, the die is preferably composed of complementary sections 13 and 14, the peripheral portions of which form a circumferential segmental groove 15 which surrounds and is concentric with the axis of the die, and in order to lock the sections or members of the die in coöperative relation, a 20 break joint 16 is preferably formed between them, and dowel pins 17 may also be used and the sections of the die may be detachably secured together by a suitable number of bolts 18, these bolts preferably having mutilated threads which coöperate with mutilated threads in the lower die section 14 whereby a partial turn of each bolt will either lock or unlock the die sections. The lower die section 14 is formed with a radial 25 slot or recess 19 which is adapted to receive a key or block 20, the latter being fixed to the top of its slide, the die being thereby fixed securely to its slide and rotation or displacement of the die during the bending 30 operation is prevented. A pin 21 extends vertically through the top of the slide and through the die resting thereon, the lower portion of this pin serving as a support to center a bevel gear 22, this bevel gear being 35 secured rigidly to and forming a driving connection with a yoke which is composed of the upper and lower arms 23 and 24 and the connecting head 25. In the present instance, the top of the gear 22 is formed with 40 a diametrical slot 26 in which a portion of the yoke arm 24 rests, and hence, rotation of the gear 22 will cause the yoke to swing about the pin 21 as an axis. The upper arm 23 of the yoke is attached to the upper portion of the pin 21 and a nut 27 serves to retain the parts in coöperative relation. The 45 pin 21 is supported on the slide by a nut 28 which is threaded on the pin and coöperates with the upper side of the slide, this nut being accommodated by the radial slot 19 in the lower die member 14. The yoke composed of the arms 23 and 24 and the connecting head 25 carries the die block 11 or 12 as the case may be. Each die block is formed 50 with a segmental groove 29 which conforms

in its radius to the diameter of the tubing or material to be bent, the groove 29 of the die block and the circumferential groove 15 of the respective die being complementary. In order to avoid flattening of tubing while the 70 same is being bent, the segmental groove 29 of the die block preferably comprises a semi-circle, the sides of the groove continuing at a tangent to the semi-circle whereby they may lap past the diametrical center of the tubing and thereby prevent lateral expansion or flattening of the tubing while the same is being bent, the sides of the tubing being confined by the grooves in the die and die block and thereby retained in proper 75 form.

Each die block is adjustable longitudinally between the arms 23 and 24 in order to accommodate dies for tubing or rods of different dimensions for bends of different 80 radii and also to enable the tubing or rods to be inserted and removed prior and subsequent to the bending operation. Each die block is connected to a cross-head 30 which is also movable longitudinally between the 85 arms 23 and 24 of the yoke, the die blocks being preferably attached to the cross-head whereby it will be advanced and retracted according to the movements of the cross-head. In the present instance, a pair of 90 blocks 31 are secured to the rear side of each of the die blocks 11 and 12, and a complementary dove-tailed block 32 is secured to the forward face of the cross-head 30, these blocks forming an operative connection between each cross-head and its respective die block. A slide 33 is also arranged to operate longitudinally between the arms 23 and 24, this slide being actuated by a screw 95 34 which is threaded in the connecting head 100 25 and is provided with a hand-wheel 36 whereby it may be adjusted. Preferably, the slide 33 is so connected to the screw 34 that it will be retracted as well as advanced by the screw, a pin 37 being used in the 105 present instance which is attached to the slide 33 and operates in a circumferential groove 38 formed in the adjacent end of the screw. Means is also provided for locking 110 the screw 34 at the different desired adjustments according to the size of die used and the diameter of the tubing being handled, the head 25 in the present instance being splined to form a clamp for the screw and a bolt 39 connects the splined portions of 115 the clamp and serves to tighten it upon the screw after the latter has been adjusted. According to the present invention, the screw 34 is adjusted according to the dimensions of the die and the tubing or material 120 being handled, and when so adjusted, the screw is locked by the clamp-operating bolt 39 and the opening and closing movements of the die block to receive the tubing preparatory to the bending operation and to 125 130

bear upon the tubing during the bending operation are effected by a cam which may be quickly and easily manipulated. In the present instance, a cam 40 is used, this cam being pivoted on a pin 41 attached to the slide 33, the cam having a flattened or reduced side 42 and a handle 43 whereby the cam may be rotated either to bring the flattened or reduced side thereof against the rear side of the cross-head 30, thereby enabling the die block 12 to be retracted and the tube inserted or removed, and when the handle 43 is manipulated to bring the concentric portion of the cam adjacent to the handle into engagement with the rear side of the cross-head 30, as shown in Fig. 2, the die block 12 is forced forward and locked in such position. The handle 43 is so located on the cam with respect to the flattened or reduced portion 42 thereof that the handle is adapted to abut against the adjacent side or corner of the cross-head 30 when the cam is in locked position, and the swinging movement of the yoke during the bending operation takes place in a direction which will cause this handle 43 to bear firmly against the cross-head, thereby locking the cam in operative position and positively preventing any backward yield of the die block. When the bending operation has been completed, the interruption of the movement of the yoke will relieve the pressure on the handle 43 and the latter may then be easily turned to release the cam and permit the die block to release the bent tubing. These yokes may be so adjusted as to operate from either side of the machine. When single bends or more than a half circle are to be made, the removal of the tube at the completion of the bending operation is provided for by first removing the upper die member 13. The die members 13 are each provided with a radial slot 44 and their removal is effected by first disengaging the screws 18 from the lower die members and by then turning the members 13 to positions wherein their slots 44 aline with the arms 23 of the yokes in the position which the latter occupy at the completion of the bending operation. The respective member 13 is thereupon lifted from position and the tube is thus freed from the bending die. The removal of the bent tube from the machine is then effected by manipulating the tube so as to bring the open space between the end of its bend and its body in alinement with the arms 23 of the yoke, and thereupon lifting the tube free of the yoke.

In a machine of the type shown wherein two bending operations are capable of being performed simultaneously, it is preferable to operate the bending yoke positively and from a common operating shaft in order that ample power may be exerted to effect the two bending operations without strain-

ing the machine. In the present instance, a shaft 45 is employed, this shaft being mounted in a bearing 46 at each end of the bed 1 of the machine and is also preferably provided with intermediate bearings 47, 70 these intermediate bearings being fixed to the sides of the bed and accommodate between them a driving gear 48 which is keyed or fixed to the shaft. The shaft 45 is formed with a longitudinal key-way 49 and a bevel pinion 50 is slidably mounted on each end of the shaft, a key or feather 51 serving to spline each pinion to the shaft. The pinions 50 are adapted to coöperate with the respective bevel gears 22 which operate the respective die blocks. The present invention provides means for simultaneously adjusting the slides to vary the distance between the bending dies and the pinions 50 which operate the gears 22 carried by the slides, such means consisting in the present instance of a screw having right and left-hand threads 52 and 53 toward its opposite ends, each end of the screw being journaled in a bearing 54 at the respective 90 end of the bed. Each slide, 3 or 4, as the case may be, is provided with a downwardly extending arm 55 which has a threaded bushing 56 fitted immovably therein and coöperative with the respective thread on 95 the screw. Each pinion 50 is positioned longitudinally on the shaft 45 by a fork 57, and the lower portion of this fork is provided with a threaded bushing 58, the latter coöperating also with the corresponding 100 thread on the screw. With this construction, rotation of the screw will cause the right and left-hand threads 52 and 53 thereon to operate on the respective slides and pinions to shift them simultaneously in opposite directions and thereby adjust the distance between the bending dies, each pinion shifting in unison with its respective slide and being maintained by the screw in coöperative relation with the gear 22 thereon. In some 110 instances, it may be desirable to render the bending mechanism for one of the slides inoperative, and to do this, it is only necessary to shift the respective pinion 50 out of engagement with its corresponding gear 22. 115 To render this possible, the bushing 58 may be retained normally in coöperative relation with its respective pinion fork 57 by a removable nut 59 and a pin 60 may be used to prevent rotation of the bushing in the 120 pinion fork, removal of the nut 59 and pin 60 enabling the bushing to be turned and thereby disengage the pinion from its respective gear. To enable the bending mechanism to be readily and easily adjusted to 125 vary the distance between the bending dies, the present invention provides power means for operating the screw, one end of the screw having in the present instance a gear 61 fixed thereto, and the main shaft 62 of 130

the machine is provided with a pinion 63 which is slidable and splined thereon whereby this pinion may be shifted into mesh with the gear 61 and the motion of the main shaft will be transmitted to the screw, and when the screw has operated to such an extent as to approximately adjust the distance between the bending dies, the pinion 63 may be shifted out of engagement with the pinion 61 and a hand-wheel 64 which is attached to the opposite end of the screw may be manipulated to produce an exact adjustment of the bending dies.

The shaft 45 which operates the bending mechanism is also driven from the main shaft 62, this main shaft having a pinion 65 thereon which coöperates with the gear 48. In order to enable the screw to be operated in the manner stated to vary the adjustment of the bending dies, this pinion 65 is provided with means for connecting and disconnecting it with respect to the main shaft in order that the bending mechanism may remain idle while the screw is being operated. In the present instance, one face of the pinion 65 is provided with a clutch member 66 which coöperates with a companion clutch member 67, the latter being splined on the main shaft and provided with a collar 68 which is engaged by a clutch-shifting fork 69, the latter being fixed to a rock shaft 70 which is rotatably mounted in the frame of the machine and provided with a handle 71 whereby the pinion may be readily connected and disconnected to the main shaft.

Preferably, means is provided for automatically terminating the operation of the bending mechanism when a bend of the desired angle has been made. Such means consists in the present instance of a cam 72 which is adjustably fixed to one end of the shaft 45 by a bolt 73, a suitable graduated scale or index being used to facilitate positioning of this cam 72 at different angles on the shaft. The main shaft is driven by a worm-wheel 74 which is mounted in a casing 75 and coöperates with a worm 76, the latter being fixed to a drive shaft 77 which is journaled in suitable bearings in the casing 75, and this drive shaft is provided with a driving clutch which embodies a member 78 which is fixed to the shaft 77 and a member 79 which is loose on the shaft 77 and is journaled on a bushing 80 thereon. The clutch member 79 forms part of a driving pulley 81 which may be operated by a belt or other suitable means. A loose collar 82 is interposed between the hub of the pulley 81 and the clutch member 78, this collar being acted on by spring-pressed plungers or pins 83 which operate normally to yieldably hold the clutch members 78 and 79 in disengaged relation. The pulley 81 constituting a part of the shiftable clutch member is provided with a pair of dogs 84 which have

projections 85 arranged to coöperate with a fixed collar 86 on the shaft 77, the other ends of the dogs being arranged to coöperate with a cone 87 which is shiftable on the shaft 77 by a hand-lever 88, entrance of the cone 87 between the dogs 84 turning them and causing the projections 85 thereon to abut against the collar 86, with the result that the pulley 81 carrying the clutch member 79 is shifted into driving engagement with the fixed clutch member 78. Means is provided for automatically holding the clutch in driving condition until a bend of the desired angle has been made. Such means consists, in the present instance, of a rod 89 which is operatively connected to the hand-lever 88 and is provided with a tension spring 90 which normally tends to shift the hand-lever 88 in a direction to permit disengagement of the clutch. A latch 91, however, is carried by and pivotally connected to the rod 89 and is adapted to engage a dog 92 fixed to the casing 75 when the lever 88 has been shifted in a direction to engage the clutch, a spring 93 serving to retain the latch 91 in locked position, this spring encircling a bolt 94 which is attached to the latch. A rock shaft 95 is mounted between the casing 75 and the frame of the machine and carries at one end an arm 96 which is arranged to be engaged by the cam 72 on the shaft 45 when such shaft has rotated sufficiently to produce a bend of the desired degree, and an arm 97 is fixed to the opposite end of this rock shaft and is arranged to engage and depress the bolt 94 when the rock shaft is operated by the arm 96, depression of the bolt 94 disengaging the latch 91 from the dog 92 and permitting the spring 90 to operate the rod 89 in a direction to cause disengagement of the clutch whereby the operation of the bending mechanism is interrupted. A hand-lever 98 may be attached to the rock shaft 95 and used for the purpose of drawing the arm 96 out of engagement with the cam 72 and thereby stopping the machine manually and at any desired moment, a tension spring 99, however, operating ordinarily to retain the arm 96 in position until engaged and actuated by the cam 72.

A gage is preferably provided in order to facilitate the positioning of the tubing or metal in the machine preparatory to the bending operation, this gage in the present instance consisting of a rod 100 which extends longitudinally of the machine and is slideable in bearings 101, one end of this rod being provided with an arm 102 which is arranged to occupy a position in alignment with the tubing when inserted in the machine and preparatory to the bending operation, as shown in Fig. 2, and a clamp 103 serves to retain the gage in different adjusted positions. A pair of abutments 104 and 105

105 are provided to sustain the stress of bending the tubing or rod, those shown in the present instance being located adjacent to the respective bending dies and are adjustable to accommodate tubing or rods of different diameters for which purpose the rear sides of the abutments are beveled and coöperate with correspondingly beveled surfaces of lugs 106 and 107, the latter being 10 fixed to the respective slides.

10 In operating a bending machine constructed in accordance with the present invention, the tubing or rod of appropriate length is inserted lengthwise into the machine while the die blocks occupy the positions shown in Fig. 2, the tubing or rod passing between the dies and their respective die blocks while the latter are relieved of pressure by their cams and the arm 102 15 of the gage serves to position the tubing or rod longitudinally in order that the bends will be made at the desired points. The cams 42 are then turned, forcing the die blocks toward the respective dies, and the 20 hand-lever 88 is then shifted to engage the driving clutch which latter is retained in driving condition by the latch 91. The shaft 53 is thus set into operation, causing the bevel pinions 50 thereon to swing the die 25 blocks about the respective dies and hence bending the tubing. The bending operation continues until the cam 72 which has been previously set at an appropriate angle strikes and lowers the arm 96, the latter operating the rock shaft 95 and thereby releasing the latch 91, whereupon the operation of the machine is interrupted.

30 I claim as my invention:—

1. In a bending machine, the combination 35 of a plurality of bending dies and co-operating die blocks, operating gears connected to the respective die blocks, a common operating shaft having gears thereon coöoperative with the respective operating 40 gears for the die blocks, and means for disconnecting one of the gears on said shaft from the operating gear for the respective die block.

2. In a bending machine, the combination 45 of a pair of bending dies and a pair of co-operating die blocks having operating gears therefor, a common operating shaft for the die blocks having driving gears slidably longitudinally thereon, a screw operative to 50 shift the dies to vary the distance between them and to shift said gears correspondingly to maintain operative relation between them and the operating gears for the respective die blocks, and means for rendering the shifting screw inoperative relatively to one of said gears on the operating shaft whereby such gear may be disengaged from the operating gear for the respective die block.

65 3. In a bending machine, the combination

of a die, a yoke mounted to swing about the die, a die block carried by the yoke, a slide also carried by the yoke and adjustable lengthwise thereof, and a cam operative between the slide and die block to shift the latter toward the die and to lock it in such position, the cam having a handle which, when the cam is in locking position, engages the die block at a point whereby the drag on the latter will tend to maintain the locking 70 position of the cam.

4. In a bending machine, the combination of a circular die, and a yoke having arms arranged above and below the die and carrying a die block mounted to swing about the 80 die, the die having a circumferential groove and being composed of complementary members joined in the plane of said groove, one of said die members being notched to permit its removal from the adjacent yoke arm. 85

5. In a bending machine, the combination of a circular die and a yoke having arms arranged above and below the die and carrying a die block mounted to swing about the die, the die having a circumferential 90 groove and being composed of complementary members joined in the plane of said groove and connected whereby one of said members may be rotated on the other, the said rotatable member being provided with a radial slot to permit its removal from the adjacent yoke arm and with means for normally locking it against rotation on its companion member. 95

6. In a bending machine, the combination 100 of a slide, a circular die mounted on the slide and having a recess in its under face, a block secured to the slide and engaging in the recess to hold the die against rotation, a pin passing through the slide and the die 105 and having an intermediate threaded portion, a nut engaging with said threaded portion, resting upon the slide, and fitted in the said recess of the die, a yoke comprising upper and lower connected arms through which 110 said pin passes, a die block carried by the yoke for coöperation with the die, the yoke being rotatable about the die and the lower arm of the yoke being disposed under the slide, and a gear wheel mounted upon said pin below the lower arm of the yoke and having a recess in its face adjoining the yoke in which the lower arm of the yoke engages, whereby said yoke may be rotated 115 with said gear wheel. 120

7. In a bending machine, the combination of a slide, a die carried thereby, a die block coöoperating with the die, a rotatable element carrying the die block, a bevel pinion associated with said rotatable element and mounted below the slide, an adjusting screw, a slide having a depending arm which has threaded engagement with said adjusting screw, an operating shaft, a bevel pinion 125 slidably on said operating shaft and having 130

driving engagement with said first named pinion, a bracket carrying said last named bevel pinion, and means removably associated with said bracket and forming an operative connection between the same and the adjusting screw.

In testimony whereof I have hereunto set

my hand in presence of two subscribing witnesses.
